10 Claims

ABSTRACT OF THE DISCLOSURE

Disclosed herein are the 8,19-epoxysteroids, 8,19-epoxyandrosta - 4,6 - diene - 3,17 - dione, 8,19 - epoxy - 17 β -hydroxyandrosta - 4,6 - dien - 3 - one and the 17 - lower acyl esters of the latter compound. The compounds are useful for lowering cholesterol concentrations in the blood serum and inhibiting gonadotrophin secretion. Methods for the preparation and use of these 8,19-epoxysteroids are given.

BACKGROUND OF THE INVENTION

This invention relates to new 8,19-epoxysteroids, to processes used for their synthesis and to intermediates used in these processes.

The 8,19-epoxysteroids of this invention have been found to possess useful pharmacologic properties, such as lowering the cholesterol concentrations in the blood serum and inhibiting gonadotrophin secretion without eliciting undesirable side effects. These properties render the 8,19-epoxysteroids of this invention useful agents for treating such conditions as hypercholesterolemia and the menopausal syndrome, respectively.

SUMMARY OF THE INVENTION

The 8,19-epoxysteroids of this invention may be represented by the following general Formula I:

in which R¹ and R² together represent a ketonic oxygen or R¹ represents hydrogen and R² represents hydroxyl or lower acyloxy.

DETAILS OF THE INVENTION

The 8,19-epoxysteroids of this invention have been found to possess interesting pharmacological properties. More particularly, these compounds, in standard pharmacological tests, for example, in a procedure similar to that described by M. Kraml et al., J. Med. Chem., 7, 500 (1964) for the testing of agents affecting cholesterol concentrations in the blood serum, have exhibited activities as cholesterol lowering agents.

When the compounds of this invention are employed as cholesterol lowering agents in warm-blooded animals, e.g., in rats, alone or in combination with pharmacologically acceptable carriers, the dosage of the compounds and the proportion of carriers is determined by the solubility and chemical nature of the compound, by the chosen route of administration and by standard biological practice. For example, the compounds may be administered orally in solid form containing such excipients as starch, lactose, certain types of clay, lubricants such as magnesium stearate, and similar ingredients. They may also be administered orally in the form of solutions, or they may be

2

injected parenterally. For parenteral administration the compounds of this invention may be administered in the form of sterile solutions containing other solutes, for example, sodium chloride or glucose to make the solution isotonic.

The dosage of the compounds of this invention will vary with the form of administration and the particular compound chosen, as well as with the particular host under treatment. Generally, treatment is initiated with small dosages substantially less than the optimum dose of the compound. Thereafter, the dosage is increased by small increments until the optimum effect under the circumstances is reached.

In general, the compounds of this invention are most desirably administered at a concentration dosage level which will generally afford effective results without causing any harmful side effects, and preferably at a level that is in a range of from about 5 mg. to about 100 mg. per kilo body weight per day, although certain variations will occur as noted above. However, a dosage level in which the range is about 25 mg. to about 50 mg. per kilo body weight per day is most desirably employed in order to achieve effective results.

Furthermore, the 8,19-epoxysteroids of this invention possess antigenadotrophic activity. More particularly, the 8,19-epoxysteroids exhibit parenteral and oral activity when tested in standard pharmacological tests for antigenadotrophic activity such as, for example, the test described by C. Revesz and C. I. Chappel, J. Reprod. Fert., 12, 473 (1966). When the 8,19-epoxysteroids of this invention are used as antigenadotrophic agents, they may be employed as described above for their use as cholesterol lowering agents.

The 8,19-epoxysteroids of this invention may be conveniently prepared by a process schematically represented as follows:

in which R¹ and R² together represent a ketonic oxygen or R¹ represents hydrogen and R² represents hydroxyl.

The starting materials of Formula II are 19-hydroxyandrosta-4,7-diene-3,17-dione (II; R¹ and R²=0), described by G. Kruger, U.S. Pat. No. 3,325,519 and Netherlands Pat. No. 66/03491 and 17 β ,19-dihydroxyandrosta-4,7-dien-3-one (11; R¹=H and R²=OH).

17 β ,19-dihydroxyandrosta-4,7-dien-3-one is readily prepared by reduction of 19-hydroxyandrosta-4,7-diene-3,17-dione with sodium borohydride.

Oxidation of the above two starting materials of Formula II with ferric chloride yields the corresponding 8,19-epoxysteroids of Formula I in which R¹ and R² are together a ketonic oxygen or R¹ is hydrogen and R² is hydroxyl, respectively. Satisfactory conditions for this oxidation include the use of 5-15 molar equivalents of ferric chloride; a reaction time of 1-60 minutes, preferably 3-20 minutes; a temperature range of 0 to 40° C., preferably 15 to 25° C.; and the use of tetrahydrofuran, methanol, a mixture of tetrahydrofuran and methanol or ethyl acetate as solvent.

Alternatively, the conversion of the above starting materials of Formula II to the 8,19-epoxysteroids of Formula I in which R¹ and R² are together a ketonic oxygen or R¹ is hydrogen and R² is hydroxyl may be effected by treat-

ing said starting materials with a N-haloacetamide or N-halosuccinimide, for example, N-bromo- or N-chloroacetamide, or N-bromo- or N-chlorosuccinimide, in a solution of an aromatic base, preferably pyridine, to yield an intermediate 7-halo derivative of Formula II

III.

in which R¹ and R² are as defined in the last instance and X represents a halogen such as, for example, bromine or chlorine. This reaction is accomplished most effectively using temperatures ranging from 0 to 30° C. and a reaction period ranging from one to six hours. Subsequent treatment of the intermediate 7-halo derivative of Formula III with a proton acceptor, preferably pyridine, at elevated temperatures, preferably 80–115° C., for a period ranging from five minutes to six hours, preferably 10–30 minutes, affords the 8,19-epoxysteroids of Formula I in which R¹ and R² together represent ketonic oxygen or R¹ is a hydrogen and R² is hydroxyl.

The 17-lower acyl esters of 8,19-epoxy-17 β -hydroxyandrosta-4,6-dien-3-one (I; R¹=H and R²=OH), may be readily prepared by treating 8,19-epoxy-17 β -hydroxyandrosta-4,6-dien-3-one, obtained by either of the above two processes, with the appropriate lower acyl anhydride or lower acyl halide in the presence of a proton acceptor, preferably pyridine.

In a related aspect of this invention, the 8,19-epoxysteroid I [R¹=H and R²=OCOC(CH₃)₃], may be obtained directly by utilizing the manipulative procedures for either of the two processes just discussed. In this case, 17 β ,19-dihydroxyandrosta-4,7-dien-3-one 17-pivalate.

is used as starting material and is either treated as described above with ferric chloride or the two-step process involving treatment with a N-haloacetamide or N-halosuccinimide followed by treatment with an aromatic base. Said starting material is obtained by converting 6 β ,19-epoxy-17 β -hydroxyandrosta-4-en-3-one, described by K. Heusler, et al., *Experientia*, 18, 464 (1962), to its corresponding 17-pivalate by treatment with pivaloyl chloride or pivalic anhydride in pyridine solution, followed by treatment of the resulting pivalate (IV, see below) with acetic anhydride and p-toluenesulfonic acid and subsequent treatment of the then obtained 19-acetate of 17 β ,19-dihydroxyandrosta-4,6-dien-3-one pivalate under mild hydrolysis conditions to afford 17 β ,19-dihydroxyandrosta-4,6-dien-3-one pivalate which may readily be converted to the corresponding $\Delta^{4,6}$ -3-dien-3-ketosteroid, the said starting material, according to the conditions used to convert $\Delta^{4,6}$ -3-ketosteroids to $\Delta^{4,7}$ -3-ketosteroids described by Kruger, cited above.

The 8,19-epoxysteroids of this invention may also be prepared by another process using 6 β ,19-epoxy-17 β -hydroxyandrosta-4-en-3-one pivalate (IV) described above.

In this process the use of the pivalate ester, 6 β ,19-epoxy-17 β -hydroxyandrosta-4-en-3-one pivalate, serves a two-fold purpose. On the one hand, this ester group is retained by the intermediates in the process and yields directly the compound of Formula I in which R¹ is hydrogen and R² is the pivaloyloxy group. On the other hand, it serves as a protecting group for the 17 β -hydroxyl group during the process, allowing a final transformation to other 8,19-epoxysteroids of Formula I.

Regarding the use of the pivalate ester as a protecting group, it is apparent that other protecting groups may be used also, for example, the benzyl group or other such suitable groups described by F. N. McOmie, "Protective

Groups," *Advances in Organic Chemistry*, 3, 216–251 (1963). The use of other suitable protecting groups is considered to be within the scope of the present invention.

This present process may be illustrated by the following formulae in which R³ represents hydrogen or lower acyloxy.

In practising this present process, 6 β ,19-epoxy-17-hydroxyandrosta-4-en-3-one (IV) is treated with sulfonyl chloride and a proton acceptor, preferably collidine, with or without an inert solvent, for example, carbon tetrachloride, at an elevated temperature, preferably 40 to 80° C., to yield the 4-chloro derivative of Formula V. The latter compound is transformed to the $\Delta^{4,6}$ -3-ketone of Formula VI in which R³ represents a lower acyl group by treatment with lower acyl anhydride, for example, acetic anhydride, and an acid catalyst, for example, p-toluenesulfonic acid. The $\Delta^{4,6}$ -3-ketone of Formula VI in which R³ is a lower acyl group is then converted to the corresponding $\Delta^{4,6}$ -3-ketone of Formula VI in which R³ is a hydrogen by preferential hydrolysis, for example, under mild basic conditions such as employing an aqueous solution of potassium hydroxide, at room temperature.

When the $\Delta^{4,6}$ -3-ketone of Formula VI (R³=H), thus obtained, is then subjected to the deconjugation conditions used to convert $\Delta^{4,6}$ -3-ketosteroids to corresponding $\Delta^{4,7}$ -3-ketosteroids, described by Kruger, cited above, the precipitate obtained on acidification of the reaction mixture is the corresponding 4-chloro-3,5,7-trien-3-ol of Formula VII and not the expected corresponding $\Delta^{4,7}$ -3-ketosteroid. It should be noted, however, that the 4-chloro-3,5,7-trien-3-ol of Formula VII rearranges to 4-chloro-17 β ,19-dihydroxyandrosta-4,7-dien-3-one 17-pivalate on prolonged standing, for example, ten hours at room temperature in a nitrogen atmosphere. Hence it is desirable to effect the conversions described below for this compound of Formula VII as soon as possible after its isolation.

The unexpected isolation of the above 4-chloro-3,5,7-trien-3-ol is the key step which allows the preparation of the 8,19-epoxysteroids of this invention by this present unique process. Accordingly, I have found that attempted acylation of the 4-chloro-3,5,7-trien-3-ol VII, isolated as described above, using an acyl anhydride, for example, acetic anhydride, in pyridine, readily yielded the corresponding 8,19-epoxy-17 β -hydroxyandrosta-4,6-dien-3-one [I; R¹=H and R²=OCOC(CH₃)₃].

Subsequently it was found that the 4-chloro-3,5,7-trien-3-ol (VII) may be conveniently and readily transformed into 8,19-epoxy-17 β -hydroxyandrosta-4,6-dien-3-one by simple treatment with a basic aromatic solvent at tempera-

ture ranging from 0° to 115° C. and using reaction times from one minute to 24 hours. Convenient reaction times and temperatures for this reaction are 10 hours at room temperature or two hours at 80° C. and a preferred basic aromatic solvent is pyridine.

8,19-epoxy-17 β -hydroxyandrosta-4,6-dien-3-one may be converted to the other 8,19-epoxysteroids of Formula I of this invention by the following methods:

(1) Said compound may be hydrolyzed to yield the corresponding 17 β -ol derivative, (I; R¹=H and R²=OH) which may then be converted to the desired 17-lower acyl ester derivative of this invention by the acylation procedure, described above. Preferred conditions for this hydrolysis include heating 8,19-epoxy-17 β -hydroxyandrosta-4,6-dien-3-one pivalate in 10% potassium hydroxide in aqueous methanol for 20 hours.

(2) The 17 β -ol derivative (I; R¹=H and R²=OH), obtained by above method (1), may be oxidized to 8,19-epoxyandrosta-4,6-diene-3,17-dione by the usual methods for converting 17 β -ol steroids to 17-ketosteroids, for example, see methods described by H. J. E. Loewenthal, Tetrahedron, 6, 295-299 (1959) or by C. Djerassi in "Steroid Reactions," Holden-Day, Inc., San Francisco, 1963, pp. 89-154.

The following examples will further illustrate this invention.

EXAMPLE 1

To a solution of 19-hydroxyandrosta-4,7-diene-3,17-dione (1.0 g.), in 9.5 ml. of methanol and 0.5 ml. of pyridine, sodium borohydride (0.1 g.), is added. The reaction mixture is stirred for three minutes and then diluted with 60 ml. of water. The solid precipitate is collected, washed with water, dried, and recrystallized from methanol-water to yield 17 β ,19-dihydroxyandrosta-4,7-dien-3-one as colorless crystals, M.P. 248-260° C.

EXAMPLE 2

A solution of 5.0 g. of 6 β ,19-epoxy-17 β -hydroxyandrosta-4-en-3-one in 20 ml. of pyridine is heated with 7.5 ml. of pivaloyl chloride at 100° C. under nitrogen for two hours. The reaction mixture is diluted with 100 ml. of water and allowed to stand at room temperature for one hour during which time the supernatant oil crystallized. The crystals are collected, dried at 60° C. and recrystallized from ethanol to afford 6 β ,19-epoxy-17 β -hydroxyandrosta-4-en-3-one pivalate; M.P. 157-158° C.

$\lambda_{\text{max}}^{\text{ECD}}$ 238 m μ (ϵ 14,300)

The latter compound (10.0 g.) mixed with 0.1 g. of toluenesulfonic acid and 3 ml. of acetic acid is heated at 100° C. for 40 minutes whereupon 50 ml. of water is added at a slow rate. Extraction with methylene chloride, drying and evaporation yields the crude 19-acetate of 17 β ,19-dihydroxyandrosta-4,6-dien-3-one 17-pivalate, which is dissolved in 10 ml. of methanol and left to stand at room temperature with 0.05 g. of sodium methoxide for 4 hours, whereupon 0.1 ml. of glacial acetic acid is added. Evaporation and recrystallization from methanol yields 17 β ,19-dihydroxyandrosta-4,6-dien-3-one 17-pivalate; M.P. 191-192° C.

$\gamma_{\text{max}}^{\text{CHCl}_3}$ 3640, 3460, 1715, 1650, 1615 and 1585 cm.⁻¹, $\lambda_{\text{max}}^{\text{ECD}}$ 283 m μ (ϵ 26,600)

17 β ,19-dihydroxyandrosta-4,6-dien-3-one 17-pivalate, obtained as described above, is then converted to 17 β ,19-dihydroxyandrosta-4,7-dien-3-one pivalate according to the procedure of Kruger, cited above, for converting $\Delta^{4,6,3}$ -ketosteroids to $\Delta^{4,7,3}$ -ketosteroids.

Example 3

To 19-hydroxyandrosta-4,7-diene-3,17-dione (5.0 g.) dissolved in 250 ml. of tetrahydrofuran-methanol (1:1) is added 20 g. of ferric chloride. The solution is stirred under nitrogen for 20 minutes whereupon 250 ml. of ethyl acetate and 750 ml. of water are added. The ethyl

acetate phase is separated and washed with water, dried with sodium sulfate and concentrated to a thick paste. Filtration yields yellow crystals which show a single spot on thin layer chromatography. Recrystallization of the crystals from ethyl acetate yields pure 8,19-epoxyandrosta-4,6-diene-3,17-dione (I; R¹ and R²=O); M.P. 224-226° C.,

$\lambda_{\text{max}}^{\text{ECD}}$ 289 m μ (ϵ =24,400), $\gamma_{\text{max}}^{\text{CHCl}_3}$ 1740, 1665, 1619 and 1581 cm.⁻¹

In the same manner, but using an equivalent amount of 17 β ,19-dihydroxyandrosta-4,7-dien-3-one, prepared as described in Example 1, instead of 19-hydroxyandrosta-4,7-dien-3,17-dione, 8,19-epoxy-17 β -hydroxyandrosta-4,6-dien-3-one (I; R¹=H and R²=OH), M.P. 169-171° C., is obtained.

In the same manner, but using an equivalent amount of 17 β ,19-dihydroxyandrosta-4,7-dien-3-one 17-pivalate, prepared as described in Example 2, instead of 19-hydroxyandrosta-4,7-dien-3,17-dione, 8,19-epoxy-17 β -hydroxyandrosta-4,6-dien-3-one pivalate [I; R¹=H and R²=OCOC(CH₃)₃], M.P. 195.5-196° C.,

$\gamma_{\text{max}}^{\text{CHCl}_3}$ 1720, 1660, and 1615 cm.⁻¹

after recrystallization from methanol, is obtained.

Example 4

To a solution of 19-hydroxyandrosta-4,7-dien-3,17-dione (3.0 g.) in 30 ml. of pyridine, N-bromoacetamide (1.3 g.) is added. The reaction mixture is allowed to stand at room temperature in the dark under a nitrogen atmosphere. After two hours, an additional amount (0.69 g.) of N-bromoacetamide is added. After the mixture has been allowed to stand for a total of 4½ hours, a solution of 300 ml. of 10% sodium bisulfite is added and the mixture is extracted with ether. The ether extract is washed twice with 300 ml. of 10% sodium bisulfite, then water, dried, and evaporated to dryness to give an oil. The oil is crystallized from ether to afford 7-bromo-8,19-epoxyandrosta-4-ene-3,17-dione,

$\gamma_{\text{max}}^{\text{CHCl}_3}$ 1732, 1670 and 1623 cm.⁻¹

The latter compound (200 mg.) is dissolved in 0.5 ml. of pyridine and heated at 100° C. for 25 minutes. The reaction mixture is cooled, diluted with hexane-ethyl acetate and water. The organic phase is separated, washed with water, dried and concentrated to yield a solid, which on crystallization from ethyl acetate gives a product identical with 8,19-epoxyandrosta-4,6-diene-3,17-dione, described in Example 3.

In the same manner, but using an equivalent amount of 17 β ,19-dihydroxyandrosta-4,7-dien-3-one, prepared as described in Example 1, or its corresponding 17-pivalate, prepared as described in Example 2, instead of 19-hydroxyandrosta-4,7-dien-3,17-dione, 8,19-epoxy-17 β -hydroxyandrosta-4,6-dien-3-one or its corresponding 17-pivalate, described in Example 3, are obtained respectively. In each case, the intermediates, 7-bromo-8,19-epoxy-17 β -hydroxyandrosta-4-en-3-one or its corresponding 17-pivalate, may be isolated.

Example 5

Using the procedure described in Example 2 for the preparation of 6 β ,19-epoxy-17 β -hydroxyandrosta-4-en-3-one 17-pivalate, but using an equivalent amount of 8,19-epoxy-17 β -hydroxyandrosta-4,6-dien-3-one, described in Examples 3 and 4, instead of 6 β ,19-epoxy-17 β -hydroxyandrosta-4-en-3-one, and using an equivalent amount of acetic anhydride, propionic anhydride or butyric anhydride instead of pivaloyl chloride, 8,19-epoxy-17 β -hydroxyandrosta-4,6-dien-3-one acetate, 8,19-epoxy-17 β -hydroxyandrosta-4,6-dien-3-one propionate and 8,19-epoxy-17 β -hydroxyandrosta-4,6-dien-3-one butyrate are obtained, respectively.

Example 6

To a solution of $6\beta,19$ - epoxy - 17β - hydroxyandrost-4-en-3-one pivalate (IV, 8.0 g.) in 16 ml. of carbon tetrachloride and 8 ml. of sym.-collidine at $50^\circ C.$, a solution of 16 ml. of redistilled sulfonyl chloride in 32 ml. of carbon tetrachloride is added over a period of 4 minutes.

Stirring is continued for another 8 minutes whereupon the mixture is poured into 48 ml. of methylene chloride and 48 ml. of 2 N aqueous hydrochloric acid. The organic phase is extracted four times with aqueous hydrochloric acid and then with water. Concentration of this phase to a thick paste and filtration yields off-white crystals. Recrystallization from methanol gives 4-chloro- $6\beta,19$ -epoxy- 17β - hydroxyandrost - 4 - en - 3 - one pivalate (V), M.P. $212-214^\circ C.$,

$\lambda_{\text{max}}^{\text{EtOH}}$ 252 $m\mu$ ($\epsilon=13,450$), $\gamma_{\text{max}}^{\text{CHCl}_3}$ 1720, 1690 and 1660 cm.^{-1}

Example 7

A solution of 4-chloro - 6,19 - epoxy - 17β - hydroxyandrost-4-en-3-one (V, 3.0 g.), prepared as described in Example 6, and p-toluenesulfonic acid (3.0 g.) in 15 ml. of acetic anhydride is allowed to stand at 100° under nitrogen for 10 minutes whereupon it is poured into 150 ml. of water and stirred for one hour. The aqueous phase is decanted from the viscous resin, the resin is dissolved in benzene and the solution stirred under nitrogen with one volume of 50% aqueous potassium hydroxide for 4 hours to destroy residual amounts of acetic anhydride. The benzene phase is dried (sodium sulfate) and evaporated at reduced pressure. The residue, consisting largely of 19-acetate (VI; $R^3=\text{COCH}_3$) is dissolved in 30 ml. of methanol and left to stand with 0.3 ml. of 50% aqueous potassium hydroxide under nitrogen for one hour whereupon 0.3 ml. of glacial acetic acid is added and the mixture concentrated to a thick paste. The paste is filtered yielding off-white crystals, which after recrystallization from methanol give 4-chloro - $17\beta,19$ - dihydroxyandrost - 4,6 - dien-3-one 17-pivalate (VI; $R^3=\text{H}$), M.P. $232-233^\circ C.$,

$\lambda_{\text{max}}^{\text{EtOH}}$ 298 $m\mu$ ($\epsilon=26,700$); $\gamma_{\text{max}}^{\text{CHCl}_3}$ 3640, 3500, 1720, 1675 and 1615 cm.^{-1}

Example 8

To a solution of 4-chloro - $17\beta,19$ - dihydroxyandrost-4,6-dien - 3 - one 17-pivalate (VI; $R^3=\text{H}$, 500 mg.), prepared as described in Example 7, in 5 ml. of dimethylsulfoxide is added to 1.0 g. of sodium methoxide in one portion. The mixture is stirred briefly under nitrogen and then poured into 30 ml. of ice-cold 2 N hydrochloric acid with stirring. The solid precipitate is collected immediately on a filter and dried in high vacuum at room temperature for 20 minutes yielding 4-chloroandrost-3,5,7-triene-3,17 $\beta,19$ -triol 17-pivalate (VII),

$\lambda_{\text{max}}^{\text{MeOH}}$ 305 (shoulder)

318 (major maximum) and 333 $m\mu$ (shoulder). On standing in a nitrogen atmosphere for 10 hours the latter product rearranges to 4 - chloro - $17\beta,19$ - dihydroxyandrost-4,7-dien-3-one 17-pivalate,

$\lambda_{\text{max}}^{\text{MeOH}}$ 255 $m\mu$

The freshly prepared 4-chloroandrost - 3,5,7 - triene-3,17 $\beta,19$ -triol 17-pivalate (VII, ca. 500 mg.) is dissolved in 15 ml. of pyridine and allowed to stand at room temperature under nitrogen for 10 hours. The reaction mixture is diluted with water, and extracted with benzene. The benzene extract is dried and poured through a column of silica gel. Elution of the silica gel with benzene-ethyl acetate (10:1) yields after crystallization from methanol a product identical to 8,19-epoxy - 17β - hydroxyandrost-4,6-dien-3-one pivalate, described in Examples 3 and 4.

Treatment of 4-chloroandrost - 3,5,7 - triene-3, $17\beta,19$ -triol 17-pivalate with acetic anhydride-pyridine (1:3) instead of pyridine gives the identical product.

Example 9

A solution of 8,19 - epoxy - 17β - hydroxyandrost-4,6-dien-3-one pivalate (1.0 g.), described in Examples 3, 4 and 8, in 100 ml. of 10% methanolic potassium hydroxide solution containing 0.5 ml. of water is boiled under nitrogen for 20 hours. The reaction mixture is concentrated and diluted with water. The solid is collected, washed with water, dried and recrystallized from ethyl acetate to yield a product identical to 8,19-epoxy- 17β -hydroxyandrost-4,6-dien-3-one, described in Examples 3 and 4.

Example 10

8,9 - epoxy - 17β - hydroxyandrost - 4,6 - dien-3-one (I; $R^1=\text{H}$ and $R^2=\text{OH}$) may be converted to 8,19-epoxyandrost-4,6-dien-3,17-dione (I; R^1 and $R^2=\text{O}$) by a variety of oxidizing procedures, see Loewenthal or Djerassi, cited above.

For instance, by dissolving 0.72 g. of 8,19-epoxy- 17β -hydroxyandrost-4,6-dien-3-one in 25 ml. of acetic acid and one ml. of water, and treating dropwise the resulting solution with 0.23 g. of chromium trioxide in 2 ml. of water at room temperature, then allowing the reaction mixture to stand for two hours, followed by the addition of ethanol to decompose excess reagent, and then adding water produces a solid precipitate which may be collected, washed with water and recrystallized from ethyl acetate to afford a product identical with 8,19-epoxyandrost-4,6-diene-3,17-dione, described in Examples 3 and 4.

I claim:

1. A compound of the formula

in which R^1 and R^2 together represent a ketonic oxygen, or R^1 represents hydrogen and R^2 is selected from the group which consists of hydroxyl and lower acyloxy.

2. 8,19 - epoxyandrost - 4,6 - diene - 3,17 - dione, as claimed in claim 1.

3. 8,19 - epoxy - 17β - hydroxyandrost - 4,6 - dien-3-one, as claimed in claim 1.

4. 8,19 - epoxy - 17β - hydroxyandrost - 4,6 - dien-3-one-pivalate, as claimed in claim 1.

5. 4 - chloro - $6\beta,19$ - epoxy - 17β - hydroxyandrost-4-en-3-one-pivalate.

6. 4 - chloro - $17\beta,19$ - dihydroxyandrost - 4,6 - dien-3-one 17-pivalate.

7. 4 - chloroandrost - 3,5,7 - triene - 3,17 $\beta,19$ - triol 17-pivalate.

8. The process of preparing a compound of the formula

wherein R^1 and R^2 together represent a ketonic oxygen, or R^1 represents hydrogen and R^2 is selected from the group

9

which consists of hydroxyl and lower acyloxy, which comprises treating a compound of the formula

wherein R¹ and R² together represent a ketonic oxygen, or R¹ represents hydrogen and R² represents hydroxyl, with a molar excess of ferric chloride.

9. The process of preparing a compound of the formula

wherein R¹ and R² together represent a ketonic oxygen, or R¹ represents hydrogen and R² is selected from the group which consists of hydroxyl and lower acyloxy, which comprises treating a compound of the formula

wherein R¹ and R² together represents a ketonic oxygen, or R¹ represents hydrogen, and R² represents hydroxyl, with a reagent selected from the group which consists of

10

N-haloacetamides and N-halosuccinimides, thereby obtaining a compound of the formula

wherein R¹ and R² together represent a ketonic oxygen, or R¹ represents hydrogen and R² represents hydroxyl, and X represents a halogen: and treating said last named compound with a proton acceptor, thereby obtaining said desired compound.

10. The process of preparing a compound of the formula

wherein R¹ is hydrogen and R² is the pivaloyloxy group which comprises treating 6 β ,19-epoxy-17 β -hydroxyandrostan-4-en-3-one pivalate with sulfonyl chloride and a proton acceptor to obtain 4-chloro-6 β ,19-epoxy - 17 β - hydroxy-androstan-4-en-3-one pivalate; treating said last-named compound with a lower acyl anhydride in the presence of an acid catalyst, thereby obtaining the corresponding 19-acylate of 4-chloro-17 β ,19-dihydroxyandrosta-4,6-dien-3-one 17-pivalate; treating said last-named compound with a base to obtain 4-chloro-17 β ,19-dihydroxyandrosta-4,6-dien-3-one 17-pivalate; treating said last-named compound with a strong base following by treatment with a strong acid, thereby obtaining 4-chloroandrosta-3,5,7-triene-3,17 β ,19-triol 17-pivalate; and treating said last-named compound with a basic aromatic solvent, thereby obtaining the desired compound.

HENRY A. FRENCH, Primary Examiner

50 U.S. Cl. X.R.

260—397.4, 397.5, 999

UNITED STATES PATENT OFFICE
CERTIFICATE OF CORRECTIONPatent No. 3,637,667Dated January 25, 1972Inventor(s) Gunther Kruger

It is certified that error appears in the above-identified patent
and that said Letters Patent are hereby corrected as shown below:

Column 4, first formula, "VI" should read -- IV --

Column 4, formula V "Cl" should be inserted in position 4 so
that formula should read --

Column 4, formula VI, "OR³" should read -- OR³ --

Column 4, formula VII, the double bond in position 7,8 should
be inserted.

Column 4, line 33, "6 β ,19-epoxy-17-hydroxyandrost" should
read -- 6 β ,19-epoxy-17 β -hydroxyandrost --

UNITED STATES PATENT OFFICE
CERTIFICATE OF CORRECTION

Patent No. 3,637,667 Dated January 25, 1972

Inventor(s) Gunther Kruger

It is certified that error appears in the above-identified patent and that said Letters Patent are hereby corrected as shown below:

Column 8, line 18, "8,9-epoxy" should read -- 8,19-Epoxy --

Column 9, first formula, "-CH₂=OH" should read -- -CH₂—OH --.

Signed and sealed this 5th day of September 1972.

(SEAL)
